CLAIM

The ornamental design for a cabin hood for a vehicle with a telescopic lifter, as shown and described.

DESCRIPTION

FIG. 1 is a back-left side-top perspective view of a cabin hood for a vehicle with a telescopic lifter, showing the new design;

FIG. 2 is a left side view thereof; and,

FIG. 3 is a top view thereof.

The broken lines showing a cabin for a vehicle with a telescopic lifter illustrate unclaimed environmental structure and form no part of the claimed design. The broken lines showing a latch in FIGS. 1 and 2, and a rectangular protrusion on the side of the cabin hood in FIG. 1 show portions of the article which form no part of the claimed design.
